DESIGN FOR A COMBINED CIGARETTE
HOLDER AND WRIST CLAMP

Virginia Snellgrove, Fort Worth, Tex.

Application December 2, 1948, Serial No. 149,926

Term of patent 7 years

(Cl. D85—8)

To all whom it may concern:

Be it known that I, Virginia Snellgrove, a citizen of the United States, residing at Fort Worth, in the county of Tarrant and State of Texas, have invented a new, original, and ornamental Design for a Combined Cigarette Holder and Wrist Clamp, of which the following is a specification, reference being had to the accompanying drawing, forming part thereof.

Figure 1 is a side elevational view of a combined cigarette holder and wrist clamp showing my new design;

I claim:

The ornamental design for a combined cigarette holder and wrist clamp, substantially as shown.

VIRGINIA SNELLGROVE.
